UNITED STATES PATENT OFFICE

JOHN H. COOK, OF SALT LAKE CITY, UTAH

VALVE-ACTUATING PLATFORM

Application filed June 8, 1928. Serial No. 283,989.

The present invention relates to platforms, constituting valve actuating means, and it is particularly intended for shower baths, so that when the bather stands upon the platform, the supply of water is automatically turned into the nozzle or other distributing means.

In the accompanying drawings:

Figure 1 is a vertical sectional view 10 through the preferred form of construction.

Figure 2 is a plan view with parts broken away.

As shown, a base is employed in the form of a spider comprising a central hub 3 with 15 four radial arms 4. These arms are connected at their outer ends to angular upstanding walls 5, forming a three-sided box, the fourth side being open but the walls having inturned terminal portions 6 at the ends of said open 20 side. The arms 4 furthermore have upstanding sleeves 7 that are preferably, though not necessarily integral with the arms.

The central hub 3 terminates in an outstanding flange 8, and bolted at 9 to said 25 flange is the casing 10 of a valve mechanism. This valve mechanism is preferably substantially the same as that disclosed in my co-pending application, Serial No. 138,548, filed Sept. 29, 1926, now Patent No. 1,691,662. It 30 is provided with an internal valve seat 11 against which normally rests a ball valve 12 that is held against the seat by a spring 13. A plunger stem 14, extending through the top of the casing, constitutes actuating means 35 for opening the valve and this plunger stem has an upstanding head or knob 15.

A rectangular platform 16 is located over the base and is provided at its corners with depending sleeves 17 that slidably telescope 40 over the sleeves 7. Bolts 18, located longitudinally within the sleeves, are fixed to the platform by means of nuts 19 threaded thereon and embracing bridge portions 20 formed in the sleeves 17. The lower ends of these 45 bolts have heads 21 slideable in the lower portions of the sleeves 7 and adapted to abut internal flanges 22 formed in said sleeves 7. Coiled springs 23 are located in the sleeves with their lower ends resting on the flanges 50 22 and their upper ends bearing against the

lower nuts 19. These springs obviously serve to hold the platform in elevated position. The platform is furthermore provided with depending corner guide pieces 24 engaged in the corners of the box 5 and serving to prevent lateral displacement of the platform and acting as guides. The downward movement of the platform may be determined by its resting on the upper edges of the base walls 5, but the extent of this downward 55 movement may be varied. To this end collars 25 surround the sleeve 7 and are adjustably fixed thereto by set screws 26. These collars may be set at any height desired and as the sleeves 17 will engage the same when the platform is depressed, the downward movement of the platform is thus determined.

In any event, it will be evident that ordinarily the platform is supported by the springs 23, but that when a person stands thereupon the platform will be depressed so that the knob 15 will be moved downwardly, thereby opening the valve and permitting the free flow of water through the valve casing. It will be understood that the valve casing 70 is connected by suitable pipes, indicated at 27 to a supply and to the distributing nozzle of a shower, these pipes extending through the open side of the base box, which side is left open for that purpose.

A wear plate 28 may be secured to the underside of the platform 16 for striking the actuating knob 15 of the valve and the position of this plate may be readily varied by introducing strips between it and the underside of the platform.

From the foregoing, it is thought that the construction, operation and many advantages of the herein described invention will be apparent to those skilled in the art, without 90 further description and it will be understood that various changes in the size, shape, proportion and minor details of construction may be resorted to without departing from the spirit or sacrificing any of the advantages of the invention.

What I claim is:

1. In mechanism of the character set forth, the combination with a base spider frame, of a valve mounted on the central 100

portion of the frame, a platform located over the frame, and yielding supports for the platform mounted on the outer ends of the spider frame.

5 2. In mechanism of the character set forth, the combination with a base having an upstanding side wall having one side open, of a yieldingly supported platform over the base, and a valve operated by said platform and located in the base within the wall, the open side permitting the passage of pipes connected to said valve.

10 3. In mechanism of the character set forth, the combination with a base comprising a spider with substantially radial arms, and an upstanding housing wall connecting the arms of a platform over the base and having depending guides engaged with the housing wall, means for yieldingly supporting the platform, and a valve on the base 15 operated by the platform on its depression.

20 4. In mechanism of the character set forth, the combination with a base comprising a spider with substantially radial arms, an upstanding housing wall connected to the 25 ends thereof and upstanding sleeves on the ends of the spider arms, of a valve mounted on the central portion of the spider, a platform over the base having corner guides slidably associated with the upstanding housing 30 wall, and sleeves slidably telescoping the sleeves of the base, said platform on its depression actuating the valve, supporting springs for the platform located in the telescoping sleeves, and bolts in the sleeves and 35 carried by the platform for limiting the upward movement of the platform.

In testimony whereof, I affix my signature.
JOHN H. COOK.
